UNITED STATES PATENT OFFICE.

MARVIN D. MAIN, OF CORTLAND, NEW YORK, ASSIGNOR OF ONE-HALF TO
LYNN R. LEWIS, OF CORTLAND, NEW YORK.

PLOW.

No. 852,843.

Specification of Letters Patent.

Patented May 7, 1907.

Application filed May 11, 1906. Serial No. 316,291.

To all whom it may concern:

Be it known that I, MARVIN D. MAIN, a citizen of the United States, and a resident of Cortland, in the county of Cortland, in the State of New York, have invented new and useful Improvements in Plows, of which the following, taken in connection with the accompanying drawings, is a full, clear, and exact description.

10 This invention relates to the class of wheel-plows which have the plow proper attached directly to the beam and have the wheels mounted on two separate and independently adjustable crank-axles pivotally connected to the beam.

15 The object of this invention is to connect the crank-axles to the beam in a position which shall cause the point of the plow to be carried directly under the attachment of the 20 crank-axles and thus allow the plow to be conveniently and effectually controlled in its operation and maintain the plow in position to penetrate the ground to the desired depth.

25 The object also is to provide very strong and compact means for connecting the crank-axles separately and independently of each other and at the same time more securely to the beam and in a manner which shall effectually obviate the liability of interference with their independent adjustment. And the object furthermore is to simplify the construction and reduce the cost of manufacture of the plow. And to that end the invention consists in the improved 30 construction and combination of parts hereinafter described and illustrated in the accompanying drawings, in which

35 Figure 1 is a side elevation of a plow embodying my invention and showing the same 40 adjusted for operating on a hill-side; Fig. 2 is a perspective view of said plow adjusted for operating on flat ground; Fig. 3 is a vertical section of the attachment of the crank-axles to the plow-beam; Fig. 4 is a vertical longitudinal section of the said attachment; and Fig. 5 is a vertical transverse section of a modification of the aforesaid attachment.

45 —A— denotes the draft-beam and, —B— the plow proper which is attached directly to the beam and in line therewith in the usual manner.

50 —R—R— represent the supporting wheels which are mounted on separate and independently adjustable crank-axles —C—C—,

the construction and attachment of which to 55 the beam —A— constitute the salient feature of my invention, which is as follows, to wit:

I form each of the said axles in one piece from a stout round metal bar, the end portions of which I bend at obtuse angles from the center or main portion of the bar so as to cause the said end portions to extend horizontally in reverse directions from the inclined intermediate main portion of the axle. 60 The lower end portion —a— of the bar constitutes the journal of one of the wheels —R—, while the upper end portion —a¹— of the bar forms an arm for mounting the crank-axle on the beam —A—, and when both axles are 65 thus mounted the arms —a¹— —a¹— extending at obtuse angles from the main portions of said axles causes the said main portions to form inclined braces extending from the wheels to the sides of the beam. These 70 crank-axles are connected to the beam by suitable means to maintain the arms —a¹— —a¹— of the axles permanently in a line crossing a vertical line passing through the plow at a point near the front end thereof, 75 which is thus carried under the attachment of the crank-axles and more conveniently and effectually controlled in its operation and more securely maintained at the required depth in the ground. 80

85 In order to provide strong and compact means for securing the crank-axles to the beam and at the same time render the said axles free from each other so as to obviate liability of interference with their independent adjustment, I provide a bracket —D— formed with a bottom plate —b— which may be placed either upon the top of the beam, —A— as shown in Figs. 1, 2, 3 and 4 of the drawings, or on the bottom of said beam as shown in Fig. 5, and is rigidly attached to the beam by suitable means, as staples or clips —c— —c— embracing the beam and passing with their ends through holes in the plate —b— and provided with nuts —d— 90 for clamping the plate —b— on the beam. 95

100 The central portion of the plate —b— has projecting from it a tubular hub —h— forming pivotal bearings —e— —e— which are in a line crossing a vertical line passing through the point of the plow. The longitudinal edges of the plate —b— are formed with vertical semicircular racks —j— —j—

which are provided with round apertures —n— in range with the bearings —e— and serving as additional bearings for the axle-arms —a¹—a¹— which are thus surely supported. Said bearings terminate in proximity to the sides of the draft-beam to accommodate the inclined main portions of the crank-axes.

In order to secure the crank-axes independently of each other in their said bearings and maintain said axles free and detached from each other and thus avoid liability of interference with their independent adjustment, I dispose the racks —j—j— at a sufficient distance from the hub —h— to form between them suitable recesses for receiving closely fitting collars —l—l— formed on the lower ends of the levers —L—L—, said collars embracing the axle-arms —a¹—a¹— to which they are fastened by means of set-screws —o—o—. The interposition of the collars —l—l— between the racks and hub securely retains the crank-axes connected to the bracket.

The levers —L—L— are provided with the usual dogs —t— formed on the lower ends of the spring-actuated rods —t¹— for engaging the racks and thereby locking the levers to retain the crank-axes in their desired positions.

By means of the levers —L—L— the crank-axes can be adjusted to set the wheels in various positions to either lift the plow from the ground while going to and from the field, or to lower the plow and place it in position to operate on a hill-side or on flat ground.

In case it is desired to connect the crank-axes to the underside of the beam as shown in Fig. 5 of the drawings, I form the bottom

plate —b— of the bracket —D— with side extensions —r—r— which are grooved longitudinally and receive in their grooves the collars —l—l— of the levers —L—L—. The outer longitudinal flanges —s—s— of the 45 said grooved extensions engage the outer ends of the collars —l—l— which are fastened to the axle arms —a¹—a¹— as aforesaid, and thus retain the crank-axes connected to the bracket —D—.

It will be observed that in either of the described connections of the crank-axes to the bracket, said axles are free and detached from each other, and each is capable of being turned in its bearings and adjusted without hindrance from the other, which hindrance would be caused if the arms —a¹—a¹— were in any way connected to each other by a coupling exerting frictional holds on said arms.

What I claim as my invention is:

In a wheel-plow, the combination with the draft-beam and plow attached directly thereto, of crank-axes formed integral with supporting arms extending at obtuse angles 65 from the ends of the main portions, a bracket rigidly attached to the draft-beam and formed with pivotal bearings at its center and side edges and terminating in proximity to the sides of the beam, said bearings receiving the axle-arms and supporting the main portions of the axles inclined from the sides of the beam, and levers formed with collars embracing the axle-arms between their bearings and fastened to said axle-arms as set 70 forth and shown.

MARVIN D. MAIN. [L. S.]
